UNITED STATES PATENT OFFICE.

AUGUST W. KOEHN, OF OSHKOSH, WISCONSIN, ASSIGNOR TO THE DEARBORN COMPANY, OF CHICAGO, ILLINOIS, A CORPORATION OF ILLINOIS.

CARD TABLE.

Application filed April 25, 1923. Serial No. 634,427.

The main object of this invention is to provide a card table of improved construction.

Other objects of my invention are to provide a card table which has a frame, a top, and improved means for securing the top to the frame, and in which a cover is provided for the top and secured thereto by an improved method, the improved method by which the cover is secured to the top being particularly advantageous when it is employed in connection with my improved means for securing the top to the frame of the table.

Other objects of my invention will become apparent as the detail description progresses, reference being had to the accompanying drawing, wherein—

Fig. 1 is a fragmentary perspective view of portions of the frame and top of a card table which embodies the novel features of my invention.

Fig. 2 is a bottom plan view of the card table, and

Fig. 3 is a section taken on line 3—3 of Fig. 2.

Referring to the drawing, I prefer to disclose my invention as embodied in a card table comprising a rectangular frame 10 which is attached a plurality of legs 11. Each of the legs 11 is pivotally secured to the frame 10 as at 12, 12, and is adapted to be swung into a position wherein it lies parallel and adjacent to one of a plurality of bars 13 which form the frame 10. A plurality of hinged members 14, each of which is pivotally secured to the frame 10 by a screw 15 and to one of the legs 11, by a similar screw, not shown, provide means whereby the legs may be locked in supporting positions with respect to the frame 10. The frame 10 is adapted to receive a top 17 of paper fiber, or similar material.

The structure above described is well known in the art, my invention having to do with the manner in which a cover 18 is secured to the top 17, with means whereby the top 17 is secured to the frame 10, and with certain features embodied in the frame itself.

As shown in Figs. 1 and 2, the cover 18, which may be of cloth, leatherette, or a similar material, is drawn tightly over the upper surface of the top 17 and also around

the edges of the top 17 so that its marginal portions may be glued or otherwise secured to the under surface of the top 17 as at 20. Each of the bars 13 is provided with a shoulder 21, which shoulders 21 together serve to receive and support the marginal portions of the top 17 in a position relative to the frame 10 wherein the upper surface of the top is substantially flush with the upper surface of the frame.

The means for securing the table top to the frame 10 comprises a plurality of straps 22. Each of the straps 22 has its ends bent downwardly as at 23 to lie adjacent the inner surface of one of the bars 13. Each bent end 23 of the straps 22 is secured to its associated bar 13 by means of a plurality of wood screws 24. It will be noted that the straps 22 are diagonally arranged with respect to the frame 10 so that each strap 22 is secured to two adjacent bars 13 of the frame.

Each strap 22 is secured to the top 17 by means of a plurality of rivets 25. The upper head 26 of each rivet 25 is concealed by cover 18 and is preferably provided with a washer 27 against which the head 26 may bear. The washer 27 reinforces the material of which the top 17 is made.

It will be readily understood that in the assembly of the device the task of securing the cover 18 to the top 17 and securing the top 17 to the frame 10 is accomplished with ease. The strap 22 is first affixed to the under surface of the top 17 by means of the rivets 25, the cover 18 being then drawn taut across the upper surface of the top and around its edges so that the marginal portions of the cover may be glued to the under surface of the top in the manner aforesaid. The assembled top 17 may then be placed in the frame 10 and the screws 23 driven in place to complete the assembly of the top and frame.

The advantages of this structure are apparent. It does not make necessary the use of brads, tacks or the like, to secure the cover in place. The use of brads or tacks to secure the cover to the top or to the frame in a manner which includes piercing the cover, will eventually permit the cover to wrinkle or fold, as the walls of the apertures thus formed in the cover will yield or tear.

The diagonal straps are advantageous in that they hold the corners of the top securely in place against the adjacent shoulders 21, at the same time providing means whereby 5 the intermediate portion of each margin of the top is held against a shoulder 21, and also means for bracing the frame.

Importance is attached to the fact that the braces 22 be of flat elongated form and 10 that they extend across the corners of the top at a distance from the angles of the frame so as not to interfere with the folding of the legs of the table.

I am aware that changes in the form, construction and arrangement of parts may be 15 made without departing from the spirit and without sacrificing the advantages of the invention and I reserve the right to make all such changes as fairly fall within the scope 20 of the following claim.

I claim:

A card table comprising a polygonal frame, the upper face of which is provided with a surrounding shoulder, a top of the shape to conform to that of the frame, a 25 cover drawn tightly over the surface of the top and around its edges and having the marginal edges thereof disposed upon the under side of the top, the marginal edges of said top being mounted on said shoulders, 30 flat elongated straps each having down-turned ends, the flat portion of each strap being secured to the under side of and across the corner of said top, and having its ends secured to the vertical faces of said frame, 35 brackets secured adjacent each corner of said frame, and legs pivoted to said brackets to fold against the top.

AUGUST W. KOEHN.
